INTERNAL ROTARY VALVE—FLUID PRESSURE TRANSDUCER

Chester A. Clark, Waldorf, Md., assignor to the United States of America as represented by the Secretary of the Navy

Filed Nov. 30, 1959, Ser. No. 356,306

4 Claims. (Cl. 116—27)

(Granted under Title 35, U.S. Code (1952), sec. 266)

The invention described herein may be manufactured and used by or for the Government of the United States of America for governmental purposes without the payment of any royalties thereon or therefor.

This invention relates to sound transducers and particularly to a transducer for use underwater which operates on power supplied by a gas or liquid circulated under high pressure.

A hydraulic transducer similar to the type disclosed herein is found in patent application Serial No. 815,234. An audio signal is fed into the prior structure by passing a fluid medium therethrough which is set in vibration by an external source. Since the fluid passes through a considerable length of conduit to reach the transducer, an appreciable amount of energy is lost through the conduit walls during the transfer. A reduction of this loss is desirable, not only to improve the efficiency of the transducer, but also to provide a more concentrated radiation surface for directional sonar systems.

An object of the present invention, therefore, is to provide a transducer of the type described above wherein the audio signal is generated entirely within the transducer.

A further object of the invention is to provide a sound transducer which operates on a fluid supplied under constant pressure and includes an internal valve system for generating audio power.

A further object of the invention is to provide a plurality of the transducers described above wherein the internal valves are externally connected and phased to produce a directional source.

These and other objects of the invention are best understood with reference to the accompanying drawings wherein:

FIG. 1 shows a front view of the transducer in section to show inner detail;

FIG. 2 is a side view of the transducer in section;

FIG. 3 is an exploded view of a rotary valve shown in FIG. 2;

FIG. 4 is directional array utilizing the transducer of the invention;

FIG. 5 is a sectional view of a rotary coupling shown in FIG. 4.

Referring to FIGS. 1 and 2 wherein are shown front and side views of the transducer, the radiating surfaces consist of two flexible walls or discs 11 spaced from and separated by a wafer-shaped body portion 12. The edges of the radiating walls are sealed to the body portion by a conventional gasket and screw fastener assembly or by welding. The center of each radiating wall has a piston 13 mounted thereon, and the body member has a pair of opposed threaded inserts 14 with cylindrical recesses 15 which receive the pistons.

A fluid under pressure flows into the transducer through a pintle member 16. A rotary valve 17 mounted in the body member channels the fluid to the cylindrical recesses or openings 14. In-phase conduits 18 supplying the inner ends of the openings are used in alternation with anti-phase conduits 19 supplying the outer ends to apply a push-pull motion to the piston. Conduits 18 and 19 also are alternately rechanneled by the valve permitting fluid

2

displaced by the piston to flow out of the transducer through the pintle 16.

A more detailed view of the rotary valve is shown in FIG. 3. The center pintle member is cylindrical and contains a central circumferential and two similar end grooves 30 which are fed by an input conduit 31. A pair of intermediate grooves 32 are also provided axially spaced between adjacent pairs of the central and end grooves. The intermediate grooves feed directly into the output conduit 33. The phasing conduits 18 and 19 which feed the cylindrical recess terminate at a fixed cylindrical sleeve 34 perforated to provide a portal 35 for each of these conduits. The portal may be diamond-shaped or have other configurations to provide various input waveforms. The rotor is a hollow cylindrical member 36 with rectangular perforations 37 laid out in a specific pattern, as shown, to provide the proper switching sequence in the fluid system. The perforations are equally distributed around the circumference to provide balanced operation at high speeds.

The above system can be provided with several desirable features. Expansion tanks 20, shown in FIG. 1, may be connected to each of the input and output conduits to absorb switching transients. The valve may be driven by an hydraulic motor supplied from the same source and perhaps even from the same conduits as those supplying the pistons. The pintle, instead of being stationary, may be attached to and driven by the rotor to supply switching power to additional transducers.

FIG. 4 shows an array of transducers 50 wherein the rotors and pintles are connected to operate as a unit. The rotor shafts have also been extended through the transducer body member to facilitate coupling. All of the rotor shafts must be interconnected in such an array to provide proper phasing. For example, a single motor 53 and a number of gear boxes 54 may be used. Packing glands must of course be provided in this case for both rotor and pintle shafts to prevent the ingress of the external medium when these transducers are subjected externally to high ambient pressures. Alternatively, in such instances, the interior of the transducer may be flooded with a fluid to balance the external pressure. To equalize internal and external pressure a chamber 23 is drilled into the body which communicates with the external medium through passageway 22 and the internal medium through a flexible or sylphon diaphragm 24. The entire array may be encased in a fluid filled box 51, shown in FIG. 4. Fluid is fed into such an array through rotary coupling joints 52.

FIG. 5 shows a typical rotating coupling joint for use in the transducer array of FIG. 4. Fluid enters and leaves the joint through a pair of stationary supply conduits 60 and 61. Each supply conduit feeds one of the grooves in the joint rotor shaft 62. The rotor shaft 62 also contains a pair of conduits 63 and 64, each of which communicates with one of the rotor grooves. The motor shaft 62 may form the upper end of the pintle, so that the latter conduits feed into the conduits shown in the pintle of FIG. 3. When the pintle and valve rotor of FIG. 3 are a unit the conduits may extend uninterrupted through the valve rotor shaft to feed a subsequent transducer. This, of course, will require a much larger shaft than the shaft 38 shown in FIG. 3.

The transducer may be powered by a variety of energy sources. Liquid under pressure may be supplied, for example, by an electric or gasoline powered pump. Steam or other vapors can be generated at high pressure by boiling. An electric pumping system may be installed completely within the transducer housing eliminating the need for outside supply pipes. In some cases a scavenging line

may be desired to remove fluid which leaks into the housing.

Obviously many modifications and variations of the present invention are possible in the light of the above teachings. It is therefore to be understood that within the scope of the appended claims the invention may be practiced otherwise than as specifically described.

What is claimed is:

1. A sound transducer for use in a liquid medium comprising a pair of substantially identical spaced parallel planar wall members having transverse dimensions which are large compared to the distance therebetween, a wafer-shaped body member lying between and parallel to said wall members and having transverse dimensions substantially equal to the transverse dimensions of said wall members said wall and body members being inter-connected and sealed at their periphery, a separate piston attached to each of said wall members, said body member defining first and second cylindrical openings each receiving one of said pistons, a first conduit means for introducing a driving fluid into said cylindrical openings, a second conduit means for extracting said fluid from said openings, and a rotary valve means mounted within said body member with the axis of said valve parallel to said planar wall members to alternately open and close said first and second conduit means.

2. A transducer according to claim 1 wherein said valve comprises a hollow cylindrical rotor with a plurality of apertures therein, a cylindrical pintle mounted snugly within said rotor and having at least two circumferential grooves each in constant communication with a different one of said apertures, said pintle defining an input conduit communicating with one of said grooves and an output conduit communicating with a different one of said grooves, said rotor being mounted within said body so that said apertures register with the ends of said first and second conduits for at least one position of said rotor.

3. A transducer according to claim 2 wherein said pintle is fixed relative to said body.

4. A transducer according to claim 2 wherein said pintle is integrally attached to said rotor and said output and input conduits extend through said rotor to provide fluid coupling for a second transducer.
